OVEN RACK GLIDE

Alfons Barnsteiner, Mansfield, Ohio, assignor to Westinghouse Electric & Manufacturing Company, East Pittsburgh, Pa., a corporation of Pennsylvania

Application November 30, 1937, Serial No. 177,310

7 Claims. (Cl. 312—156)

My invention relates to ovens and more particularly to the formation and attachment of rack glides to the inner walls thereof.

According to present practice, the rack glides for ovens constitute separate members located within the ovens. In some cases, the glides have been welded or otherwise rigidly attached to the oven walls, this being done in order to permit relatively close vertical spacing of the glides, which close spacing could not be accomplished by stamping out the glides without rupturing the metal. It is, therefore, an object of my invention to provide a structure embodying stamped out glides relatively closely spaced on the side walls of the oven for supporting the rack in various positions.

A further object of my invention is to provide a method of producing an oven which has corrugated or fluted sheets operatively associated therewith, which in turn function as oven rack glides.

Another object of my invention is to provide a method and means whereby smooth corrugations or flutes may be formed closer together than the sheet material alone would permit without tearing.

Other objects of my invention will either be pointed out specifically in the course of the following description of a device embodying my invention, or will be apparent from such description.

Referring to the accompanying sheet of drawings:

Figure 1 is a perspective view of an oven constructed in accordance with my invention;

Fig. 2 is a side elevational view of the oven wall before being completely assembled;

Fig. 3 is an enlarged sectional view taken along the line III—III of Fig. 2;

Fig. 4 is an elevational view of a sheet metal strip in one step during the process of being formed;

Fig. 5 is an elevational view similar to Fig. 4 with the strip in a second processing step;

Fig. 6 is an enlarged sectional view taken along the line VI—VI of Fig. 5;

Figs. 7, 8 and 9 are views similar to Figs. 4, 5 and 6, respectively, of the modified form of my invention shown in Fig. 10;

Fig. 10 is a view similar to Fig. 2 of a modified form of my invention as applied to a portion of an oven wall; and

Fig. 11 is a partial side view corresponding to Fig. 2 with the strips operatively associated therewith.

Referring to the accompanying sheet of drawings, I show an oven casing 10 having relatively large and shallow depressed portions 12 and 12a in the side walls thereof and a plurality of corrugated metallic strips 14 operatively associated

with the side walls of the oven 10 within the depressed portions 12. The side walls 11 of the oven 10 are depressed by suitable dies caused to form the substantially rectangularly shaped depressions 12 and 12a (the latter being smaller) 5 in the sides thereof as shown in Figs. 2 and 3. The depressions 12 and 12a may be formed inwardly so that they will be viewed substantially as embossed or raised portions from the inside of the oven. Preferably at the same time that the depressed portions 12 and 12a are formed within the side walls 11 of the oven 10, elongated apertures 18 are punched within the confines of each depression. The apertures 18 are located substantially in a series of horizontal lines while an additional set of apertures 18a, formed in 10 larger depression 12 only, are slightly raised 15 from the horizontal line of the apertures 18.

The corrugated strips 14 are formed out of sheet metal blanks or strips 15 which are substantially rectangular in shape, as shown in Fig. 4. The sheet metal blank 15 is then transversely slotted with slots 20 located intermediate the points at which the corrugations 22 in oven wall are to be formed. These transverse slots 20 cut 25 therein do not intersect either edge of such strip or blank. The slotted strip 15 is then pressed within suitable dies so that as the dies mate in the sheet material between slots 20, the metal located between the slots is drawn in such manner that the flutes 22 will be formed therein as shown in Figs. 5 and 6. The metal between the slots 20 flows towards the corrugated flutes 22, permitting such flutes to be formed without actually rupturing the sheet metal. In other words, 30 the metal of the sheet metal blank 15 will flow downwardly into the forming dies in such a manner that the slots 20 will be drawn apart into irregular elliptical shaped apertures, substantially 35 as shown at 23 in Fig. 5. The metal along the 40 edge of the strip 15 adjacent to the slots 20 may be necked in due to the flow of metal substantially as shown at 25 in Fig. 5. It is to be understood that the flutes or corrugations are satisfactorily formed within the sheet metal blank with 45 out tearing the sheet primarily due to the presence of the slots 20, which permit the metal adjacent thereto to flow down into the forming dies, and in turn form the finished corrugations or flutes. 50

With the sheet metal blank 15 formed so as to form corrugated strips 14, as hereinabove described, such corrugated strips may be placed upon the outside of the side walls 11 of the oven 10 within the depressions 12 and 12a, in such position that the flutes 22 will protrude through the apertures 18 or 18a. The fluted strip 14 may then be rigidly attached to the side walls 11 in any manner desired. However, it is preferred that they be spot welded thereto. If the de- 60

pressed portion 12 be of a depth substantially equal to the thickness of the fluted strip 14, it is obvious that the outer surface of the side walls of the oven 10 will be substantially smooth, and 5 the assembly of the oven in a range does not require any special handling thereof or preparation of the parts cooperating therewith.

After the fluted strips 14 have been permanently placed within the depressed portions 12 and 12a and the flutes 22 inserted within the oven 10, the complete oven including the oven walls and the attached fluted strips may be enameled, whereupon the inner surface of the oven walls will have the appearance of a single solid structure having flutes or corrugations smoothly extending inwardly within the side walls of the oven.

By having the apertures 18 and the flutes operatively associated therewith in a horizontal line, 20 it is obvious that such flutes will support a rack 24 or the like, which may be readily slid within the oven.

If it be desired, the apertures located within the depressed portions 12 may be of considerable 25 length as shown in Fig. 10. With the oven wall being formed in such a manner, the corrugations 22 may be singly formed from sheets or blocks as shown in Figs. 7, 8 and 9, which in turn may be welded to the oven side walls 11 substantially as 30 hereinabove described. However, it is to be understood that it is preferred that the corrugations 22 be formed within a strip and the strip as a whole placed within the depressed portion 12 or 12a.

35 Various further modifications may be made in the device embodying my invention without departing from the spirit and scope thereof. Moreover, it will be understood that my invention is not limited in its application to ovens but 40 may equally well be employed in refrigerators and other devices where glides or supports are required. I desire, therefore, that only such limitations shall be placed thereon as are imposed by the prior art and the appended claims.

45 I claim as my invention:

1. In a device of the character described, the combination of a pair of oppositely disposed metal walls, each of said walls having a shallow depressed portion and an aperture entirely surrounded by the material of the wall within the boundaries of said portion, said apertures being oppositely disposed, and separate sheets of metal secured to the respective walls within said depressed portions and each having a corrugation 50 therein respectively extending through the corresponding aperture, the thickness of each of said sheets being substantially equal to the depth of said depressed portion, whereby the planes of the outer face of each sheet and of the adjacent undepressed wall portions substantially coincide to provide a relatively smooth overall surface.

2. In a device of the character described, the combination of a pair of oppositely disposed metal walls, each of said walls having an aperture 55 therein entirely surrounded by the material of the wall, said apertures being oppositely disposed, and separate sheets of metal secured to the respective walls and each having a plurality of irregular apertures therein and a corrugation between two apertures, and each corrugation extending through the corresponding wall aperture.

3. In a device of the character described, the combination of a pair of oppositely disposed metal walls, each of said walls having a shallow depressed portion and an aperture entirely sur-

rounded by the material of the wall within the boundaries of said portion, said apertures being oppositely disposed, and separate sheets of metal secured to the respective walls within said depressed portions and each having a plurality of irregular apertures therein and a corrugation between two apertures, and each corrugation extending through the corresponding wall aperture.

4. In a device of the character described, the combination of a pair of oppositely disposed metal walls, each of said walls having a plurality of apertures therein each entirely surrounded by the material of the wall, said apertures being oppositely disposed in pairs, and separate sheets of metal secured to the respective walls and each having a series of irregular apertures therein with a corrugation intermediate each pair of said irregular apertures, said corrugations in each sheet extending through the corresponding plurality of wall apertures.

5. In a device of the character described, the combination of a pair of oppositely disposed metal walls, each of said walls having a shallow depressed portion and a plurality of apertures each entirely surrounded by the material of the wall within the boundaries of said portion, said apertures being oppositely disposed in pairs, and separate sheets of metal secured to the respective walls within said depressed portions and each having a series of irregular apertures therein with a corrugation intermediate each pair of said irregular apertures, said corrugations in each sheet extending through the corresponding plurality of wall apertures.

6. In a device of the character described, an inner casing defined by a bottom wall, a top wall, and a pair of substantially vertical side walls, two of said substantially vertical walls having a plurality of shallow depressed portions formed therein and spaced longitudinally with respect to the depth of the casing and a plurality of vertically-spaced apertures entirely surrounded by the material of the walls formed within the boundaries of each depressed portion, and separate sheets of metal placed within said depressed portions substantially flush with the outside of said side walls, and each of said metal sheets having a plurality of vertically-spaced corrugations which extend through the corresponding apertures in the substantially vertical walls into the space enclosed by the casing.

7. In oven liners and the like, the combination of a substantially rectangular casing formed of sheet metal and having top, bottom, and side walls, a series of apertures being provided in intermediate portions of each side wall, said apertures on one wall being located at different elevations and respective apertures on the opposite wall being disposed at corresponding elevations, and a sheet of metal secured to the outer surface of each side wall and covering the apertures therein, each of said sheets having projections formed thereon corresponding in number and position with the apertures in the adjacent side wall of the oven and said projections extending through their corresponding apertures to provide rack supports inside the oven liner, each of said sheets also having its projections drawn from the metal of the sheet so that both the projections and the sheet are formed from a single sheet of material and each of said sheets having slots spaced between the projections to afford such forming of the projections, said slots being covered by non-apertured portions of the liner.
